UNITED STATES PATENT AND TRADEMARK OFFICE
CERTIFICATE OF CORRECTION

PATENT NO. : D655,933 S
APPLICATION NO. : 29/365471
DATED : March 20, 2012
INVENTOR(S) : Taku Kumazawa

Page 1 of 1

It is certified that error appears in the above-identified patent and that said Letters Patent is hereby corrected as shown below:

On the title page of the patent, the text following the heading "Related U.S. Application Data" should be corrected as follows:

In the first line, "Division" should be -- Continuation-in-part --.

In the sixth line, "600,465, application No. 29/365,471, which is" should be -- 600,465. This application No. 29,365,471 is also --.

In the eighth line, after "filed on Feb. 8, 2010," the phrase -- now Pat. No. Des. 656,334, -- should be inserted.

Signed and Sealed this
Twenty-sixth Day of June, 2012

David J. Kappos
Director of the United States Patent and Trademark Office
